UNITED STATES PATENT OFFICE

WILLIAM W. CLIMENSON, OF HONEY BROOK, PENNSYLVANIA

CRAYON OR PENCIL HOLDER

Application filed February 18, 1930. Serial No. 429,380.

This invention relates to crayon or pencil holders, and aims to provide novel means for supporting a crayon or pencil in a tubular holder, in such a way that the crayon or pencil may be readily moved from its inactive position to an extended position or vice versa.

An important object of the invention is to provide a device of this character which will be exceptionally cheap to manufacture, due consideration being had for the strength and durability of the device.

A still further object of the invention is to provide a device of this character which may be used as an advertising medium, the thumb piece forming a part of the device being of such a size as to permit advertising matter to be placed thereon.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view of a device constructed in accordance with the invention, illustrating a pencil used in the holder.

Figure 2 is a sectional view taken on line 2-2 of Figure 1.

Figure 3 is a sectional view taken on line 3-3 of Figure 1.

Figure 4 is a sectional view through the sleeve used in moving the pencil within the tubular holder.

Figure 5 is an elevational view illustrating the pencil and sleeve connected thereto.

Figure 6 is an elevational view of a tubular holder designed for holding a crayon.

Figure 7 is an elevational view illustrating the opposite side thereof.

Figure 8 is a sectional view taken on line 8-8 of Figure 7.

Referring to the drawings in detail, the

reference character 5 designates a tubular holder or body portion, which as shown, is provided with a longitudinal slot extended throughout the length thereof.

It is of course understood that the holder 5 is of a diameter to receive the pencil in such a way that the pencil will closely fit within the holder, the pencil in the present showing being indicated by the reference character 6. Slidably mounted on the holder 5, is a sleeve 7, which is split and provided with inwardly extended ears 8 and 9 respectively, the ear 9 being bent around one edge of the holder, adjacent to the slot, to hold the sleeve in position on the holder.

The ear 8 is sharpened to provide a blade, and extends inwardly where it may cut into the pencil, to secure the sleeve to the pencil in such a way that when the sleeve is moved, the pencil will be moved within the holder.

When the pencil is positioned within the holder, the sleeve is positioned over the holder and is moved along the holder, with the result that the blade 8 cuts into the pencil, forming a groove throughout the length of the pencil. When the sleeve has been moved to a position adjacent to the eraser end of the pencil, the sleeve is rotated slightly, breaking away a portion of the pencil adjacent to the slot, to lock the sleeve in position and prevent the sleeve from moving independently of the pencil, when the sleeve is slid along the holder.

In order that the sleeve may be moved laterally, a notch 10 is provided in the body portion or holder. This notch also presents shoulders at its ends to engage the edges of the ear or blade 8, so that when the eraser of the pencil, which is indicated by the reference character 11, is used, the pressure on the rubber will not force the pencil through the holder.

In the form of the invention as shown by Figure 6, the tubular body portion or holder is indicated by the reference character 12, the same being provided with a longitudinal slot 13 extending from the open end of the holder, to the closed end thereof. The reference character 14 designates the sleeve that is mounted on the holder, and slides

longitudinally thereof, the sleeve having an inwardly extended blade 15 to bite into the crayon, which is indicated by the reference character 16, to secure the sleeve to the crayon in such a way that movement of the sleeve will act to move the crayon longitudinally of the holder.

In this form of the invention, an enlargement 17 is formed on the sleeve, the enlargement being slightly depressed to receive the thumb of the operator so that the sleeve may be operated readily.

This enlargement of thumb piece 17 also provides a surface on which certain advertising matter may be printed, it being contemplated to construct the device in such a way that the cost of manufacture will be so low as to warrant the devices being given away as an advertising medium.

The member 17 also provides a rest for the holder, to prevent the holder from rolling when positioned on an uneven surface.

I claim:

1. In a device of the class described, a tubular holder having a slot formed throughout the length thereof, a sleeve slidably mounted on the holder, said sleeve being split, ears extending inwardly from the split portions of the sleeve, one of said ears being bent into engagement with the body portion to secure the sleeve to the body portion, the opposite ear being sharpened, and providing a blade to cut into a pencil positioned within the holder, and said holder having means cooperating with one of the ears to restrict movement of the sleeve longitudinally of the holder.

2. In a device of the class described, a holder having a slot formed throughout the length thereof, a sleeve slidably mounted on the holder and having ears extending into the slot, one of said ears adapted to engage a pencil supported within the holder to secure the pencil to the sleeve, said holder having a notch formed near one end thereof, and one of said ears adapted to move into the notch to restrict movement of the sleeve longitudinally of the holder.

In testimony that I claim the foregoing as my own, I have hereto affixed my signature.

WILLIAM W. CLIMENSON.
